(57) **CLAIM**

(21) Appl. No.: **29/125,710**

The ornamental design for an electromagnetic sound generator, as shown and described.

(22) Filed: **Jun. 29, 2000**

DESCRIPTION

(30) **Foreign Application Priority Data**

Dec. 30, 1999 (JP) 11-37317

FIG. 1 is a top view of an electromagnetic sound generator embodying our new design;

(51) LOC (7) Cl. **10-05**

FIG. 2 is a front view thereof;

(52) U.S. Cl. **D10/116**

FIG. 3 is a bottom view thereof;

(58) **Field of Search** D10/104, 106,

FIG. 4 is a rear view thereof;

D10/116, 121; D13/152, 156; 340/384.1,

FIG. 5 is a right side view thereof;

384.3, 384.7, 388.1, 390.1, 391.1, 392.1,

FIG. 6 is a left side view thereof;

392.2, 392.4

FIG. 7 is a perspective view as viewed from the upper side thereof;

(56) **References Cited**

FIG. 8 is a perspective view as viewed from the lower side thereof; and,

U.S. PATENT DOCUMENTS

FIG. 9 is an exploded perspective view thereof.
